A CORPORATION OF NEW JERSEY.

WORK-SUPPORT FOR SHOE MACHINERY.

1,147,162.

Specification of Letters Patent. Patented July 20, 1915.

Application filed October 19, 1912. Serial No. 726,702.

To all whom it may concern:

Be it known that we, JOSEPH GOULDBOURN and REGINALD B. Woodcock, residing at Leicester, Leicestershire, England, have invented certain Improvements in Work-Supports for Shoe Machinery, of which the following description, in connection with the accompanying drawings, is a specification, like reference characters on 10 the drawings indicating like parts in the several figures.

This invention relates to work supports for use in the manufacture of boots and shoes and more particularly to work supports for use in machines in which the last is subjected to heavy pressure; such machines for example as are employed for attaching heels. It is important in these machines to provide a support of such construction as to afford an adequate surface to support the last against the pressure which is brought upon it in the operation of the machine and which can also automatically adjust itself to accommodate variations in the shapes of 20 different lasts. A support of this kind is a necessity also to enable the machine to operate upon lasts which have become damaged in long use, by having one side of the crown broken down, for example.

To this end a feature of the present invention consists in the provision of a work support which includes a plate or block for the crown of a last so mounted that it can be rocked about an axis extending transversely of the last to permit the crown thereof to take up any position which is necessary in order to bring the heel seat of the shoe into the proper position to be operated upon.

As herein shown the last block, in addition to its angular rocking movement, is so mounted as to be capable of an adjusting movement of translation in the same general direction as the rocking movement.

This construction permits a wide range of adjustment of the work so that an improper location of the last pin hole in the last may be compensated for as well as an improper or defective slope in the crown surface of the last.

Another feature of the invention consists in the provision of an improved last pin of such construction that the last can be placed thereon or removed more readily than here-

tofore and also held more firmly in place 55 than has been possible in prior constructions. To this end there is provided a last pin which is formed in a plurality of parts arranged for a relative movement so that the effective diameter of the pin may be reduced when the last is to be removed or placed upon it and increased to securely hold the last after it has been placed upon the pin.

The invention further contemplates the 65 provision of automatic means arranged to effect a contracting movement of the parts of the last pin when the work support is moved into its last receiving position and to increase or expand the diameter of the pin 70 when the work support is moved into its operative position in the machine. An important advantage of this feature is that the operator may slide the last upon the last pin or remove it with facility, and nevertheless the last will be securely and tightly held by the pin as soon as the work support is moved out of its work receiving position and during the operation of the machine.

Still another feature of the invention consists in the provision of means for returning the adjustable last block to a central or initial position automatically when the work support is moved to last receiving position. As herein shown, this operation is effected 80 by the same means which controls the expansion or contraction of the last pin. This arrangement is advantageous because it simplifies the construction of the work support, but it would not be without the scope of the 85 invention to provide independent means for centering the last block and for controlling the expansion of the last pin. It is believed that heretofore means responsive to the movement of a work support have never 90 been employed to center a last block and this construction is broadly new.

These and other features of the invention will be best understood and appreciated from the following description of an embodiment thereof adapted for use in a healing machine in which the last jack is pendent. This embodiment of the invention is illustrated in the accompanying drawing, in which,—

Figure 1 is a view in side elevation partly in section; Fig. 2 is a view, also partly in section, at right angles to that shown in

Fig. 1, and Fig. 3 is a sectional view of a work support having a solid last pin.

As herein shown the novel work support of this invention is carried by the vertically movable plunger 2 of a heeling machine such as that disclosed in co-pending application Serial No. 722,270, filed September 25, 1912. At its lower end the plunger 2 is provided with an extension 4 in which is formed a horizontal guideway for a sliding plate 6. The extension 4 at its forward end is provided with a lug through which extends an adjusting screw 8 threaded into the front end of the slide 6. The screw 8 is prevented from moving longitudinally by fixed collars on each side of the lug and by turning this screw the plate and the parts carried thereby may be adjusted forwardly or rearwardly in the machine and in the direction of the longitudinal axis of the last carried by the support. The plate 4 has a centrally perforated lug 10 through which extends the pivot or spindle 12 about which the jack post 14 is arranged to swing. The spindle in this case is fast in the lug 10 and projects on each side thereof through the forked end of the jack post.

In order to reduce the pressure upon the spindle 12 in the operation of the machine 30 the arms constituting the fork of the jack post are formed with convex surfaces at their upper ends and are arranged in sliding contact with corresponding concave recesses formed in the under side of the plate 4.

35 At its lower end the jack post 14 is provided with a transversely extending dovetailed guideway in which is mounted a block 16, which will be referred to herein-after as the intermediate block. In the 40 lower surface of the intermediate block 16 is formed another transversely extending guideway but instead of being straight, as is the guideway first mentioned, this guideway is in the form of an arc of a circle. 45 Both these guideways extend in the same general direction; namely, transversely of the last. In the curved guideway, of which the concave surface is toward the last, the last block 18 is arranged to swivel so that it 50 may be canted on one side or the other of its normal central position to compensate for variations in the angular relation of the heel seat and the crown of the last.

The last pin 20 is mounted in the last 55 block 18 and comprises two separable sections having laterally projecting journal portions 22 disposed in sockets formed partly in the last block 18 and partly in a cover plate 24 which is screwed into a recess 60 formed in the outer surface of the last block. The sections of the last pin are in this manner so mounted that their outer ends may be spread apart into engagement with the sides of the last pin hole and thereby engage the last more firmly than has been

possible heretofore. The adjacent or contacting faces of the last pin sections are grooved longitudinally to receive a leaf or C-spring 26 which tends normally to maintain the two sections in their separated or expanded position. The outer ends of the spring enter holes in the last pin sections so that there is no liability of the spring becoming displaced. The upper or inner end of each section of the last pin is beveled 75 or provided with an inclined surface 28 which together form a V-shaped notch. Into this notch projects the beveled lower end of a plunger 30 which is arranged for longitudinal movement in a bore formed in 80 the center of the jack post 14. When the plunger 30 is moved downwardly its wedge-shaped end acts upon the beveled ends of the sections of the last pin to spread them and consequently to close together their outer ends and so contract the last pin.

The plunger 30 is arranged to move responsively to the movement of the jack post about its spindle 12. To this end a stationary cam 32 is rigidly secured to the 90 lower end of the lug 10 on the plate 4 and is so shaped that when the jack post 14 is swung outwardly or toward the left in Fig. 1 the plunger 30 is forced downwardly and the last pin contracted. The plunger 30 is moved upwardly and held in contact with the cam 32 by a compression spring 34 located in an enlargement of the central bore in the jack post and encircling the plunger 30. At its upper end the spring 34 bears 100 against a collar 36 fast on the plunger while at its lower end the spring bears against a portion of the jack post. Movement of the plunger 30 in the jack post is limited by a transverse pin 38 which passes through a 105 slot in the plunger.

For the convenience of the operator it is desirable to provide means for temporarily holding the jack post in its outer or last receiving position. As herein shown this is effected by means of a detent which comprises a leaf spring 40 secured by means of the screw 42 to the rear side of the jack post and having a V-shaped portion formed in its upper end. This portion of the spring 40 is adapted to fit into a notch 44 formed in the rear end of the cam piece 32. With the jack post in its forward position it requires merely a slight pressure to force the detent spring 40 out of its notch whereupon the jack post is entirely free to be moved inwardly to its operative position.

As has been intimated already, the plunger 30 which controls the expansion of the last pin 20 also serves to return the adjustable parts of the support to their central or initial position each time the jack post 14 is moved outwardly to its last receiving position. The action of the plunger in effecting this result will be apparent from Fig. 2

in which it will be noted that the wedge-shaped end of the plunger by engaging the inclined surfaces 28 of the last pin sections tends to center these sections and therefore 5 the parts to which they are connected. Sufficient clearance or lost motion to permit the last block and pin to be moved or canted to any position required in practice is provided between the wedge-end of the plunger 10 30 and the V-shaped notch formed by the sections of the last pin.

The operation of the work support constructed as hereinbefore outlined is as follows: When it is desired to place a last upon 15 the last pin 20 of the jack post the operator swings the post from its operative or heel attaching position about the spindle 12 until it is held by the detent 40 in its forward position, as indicated by the dot-and-dash 20 line in Fig. 1. As the jack post is moved from its operative position to the last receiving position the projecting part of the stationary cam 32 engages the upper end of the plunger 30 and moves it against the 25 action of its spring 34 to cause the wedge shaped lower end of the plunger to engage the V-shaped notch formed between the upper ends of the last pin sections so as to force the outer ends of these sections together in order to enable the operator easily 30 to slip the last upon the pin. After the last has been placed upon the pin the jack post is swung inwardly and the end of the plunger 30 carried off the projecting part of 35 the stationary cam. When the jack post has been moved sufficiently for this to occur the spring 34 lifts the plunger and removes its wedge-shaped end from between the ends of the last pin sections. This permits the 40 spring 26 located between the sections of the last pin to force the outer ends of the sections apart and into engagement with the sides of the last pin hole and thereby hold the last securely on the pin. The last is 45 then adjusted laterally and canted so as to bring it into the correct relationship with the heel which is to be attached before the pressure is applied to the work to force the heel and shoe together.

50 Many features of the invention may be embodied in a work support having no last pin at all or in a work support having a solid or non-expansile last pin. One form of the latter construction is illustrated in 55 Fig. 3. In the support therein shown the lower end of the jack post 14 is provided with a straight transversely disposed dovetailed guideway in which is adjustably mounted an intermediate block 50. The 60 block 50 in turn is provided in its lower surface with a transverse curved guideway for the last block 54. A solid last pin 56 is inserted in the last block 54 and held in place by a screw or bolt 58 threaded through 65 the rear side of the last block. The adjust-

able intermediate block 50 is limited in its sliding movement by a pin 52 which is secured in the lower end of the jack post 14 and projects into an opening 53 in the block 50. When the block 50 is moved in the 70 guideway in either direction the engagement of one side of the opening 53 with the pin 52 will prevent its further movement. The last pin 56 is also provided with a projection 75 57 at its upper end which projection by engaging the sides of the opening 53 in the block 50 will limit the canting movement of the last block and last pin in both directions.

Having thus described our invention, 80 what we claim as new and desire to secure by Letters Patent of the United States is:

1. A device of the class described having, in combination, a frame carrying post, a last block so connected to the post that it may 85 be rocked transversely of the last and also moved in a straight path transversely of the last, and means for adjusting the position of the post in the direction of the longitudinal axis of the last.

2. A device of the class described having, in combination, a last block having a pin mounted therein and being adjustable in a rectilinear path and also in a curved path both disposed transversely to a last on the 95 pin, and means for adjusting the block in the direction of the longitudinal axis of the last.

3. A device of the class described having, in combination, a post having a rectilinear 100 guideway formed in its end, an intermediate block adjustable in the guideway and having a curved guideway extending in the same general direction as the guideway in the post, a last block adjustable in the curved 105 guideway of the intermediate block, and a centrally disposed spindle for limiting the movement of the intermediate block and also of the last block.

4. A last support, comprising a block for 110 engaging the crown of the last which is free to rock laterally of the last so as to adjust itself automatically and distribute the supporting pressure on the surface of the crown, and means for constraining it 115 from movement longitudinally of the last.

5. A device of the class described, having in combination, an adjustable last block, a two part last pin bodily movable with the last block, and means for yieldingly separating the parts of the pin.

6. A device of the class described comprising a last support movable into and out of operative position, and an expansible last pin arranged to be expanded when the support is moved into operative position and to be freely adjustable when expanded.

7. A device of the class described comprising a last support movable into and out of operative position, an adjustable last pin 130

carrier, an expansible last pin constructed and arranged to be contracted when the support is moved out of operative position, and means for locking and unlocking the 5 carrier according to the position of the support.

8. A device of the class described comprising a last support movable into and out of operative position, a last block thereon adjustable in opposite directions from a predetermined position, and means for moving the last block into said predetermined position when the support is moved out of operative position.

15 9. A device of the class described comprising a last support movable to and from last receiving position, a last block thereon adjustable transversely in opposite directions from an initial position, and means for automatically returning the last block to said initial position when the support is moved into last receiving position.

10 10. A device of the class described comprising a last support movable to and from last receiving position, an expansible last pin adjustably mounted thereon, and means constructed and arranged for automatically returning the pin to an initial position and also for contracting it when the support is moved into last receiving position.

15 11. A device of the class described comprising a last support movable to and from last receiving position, an adjustable last block mounted thereon, and means arranged automatically to return the block to a predetermined initial position when the support is moved into last receiving position.

40 12. A device of the class described comprising a last support movable to and from last receiving position, an adjustable last block mounted thereon, and means for holding the last block in a central position until the support has been moved a predetermined distance from last receiving position and then releasing the last block so that it may be adjusted.

45 13. A device of the class described comprising a last support movable to and from last receiving position, an expansible last pin thereon, and means, responsive to the movement of the last support, for controlling the expansion of the last pin, said means being arranged to leave the last pin free for adjustment after it has been expanded.

55 14. A device of the class described comprising a last support movable about a transverse axis to and from last receiving position, a last pin comprising laterally sep-

arable sections, and means responsive to the movement of the last support about its axis for controlling the separation of the last pin sections, said means being arranged to leave the last pin free for adjustment after it has been expanded.

65

15 15. A device of the class described comprising a pivotally mounted jack post carrying an expansible last pin, and means for controlling the expansion of the last pin arranged to be moved longitudinally of the 70 jack post when the latter is swung on its pivot and to leave the last pin free for adjustment when expanded.

16. A device of the class described comprising a pivotally mounted jack post carrying an expansible last pin, a stationary cam, and a plunger for controlling the expansion of the last pin carried by the jack post and arranged to be actuated by the cam.

75

80

17. A device of the class described comprising a pivotally mounted jack post carrying at its free end an expansible last pin, a plunger slidably mounted within the jack post, a spring for moving the plunger in one direction, and a cam moving the plunger in the other direction.

85

18. A device of the class described comprising a last support movable to and from last receiving position, an adjustable and expansible last pin mounted thereon, and a single device responsible to the movement of the support for centering the last pin and contracting it.

90

19. A device of the class described comprising a last support having a last pin composed of separable sections pivotally mounted between their ends, the inner ends of the sections having oppositely disposed beveled surfaces forming a V-shaped notch, and a 100 wedge-shaped member movable into said V-shaped notch to separate the inner ends of the last pin sections.

95

20. A device of the class described comprising a jack post, a last block adjustably retained upon the post, and an expansible last pin projecting from the block and having its inner end contained within the block, thereby permitting bodily adjustment of the block on the post.
